UNITED STATES PATENT OFFICE.

JOHN H. A. BRAHTZ, OF ST. PAUL, MINNESOTA.

GRAIN-ELEVATOR.

1,342,418.

Specification of Letters Patent.

Patented June 8, 1920.

Application filed August 22, 1918. Serial No. 250,912.

To all whom it may concern:

Be it known that I, JOHN H. A. BRAHTZ, a subject of the King of Denmark, who have declared my intention to become a citizen of the United States, residing at St. Paul, in the county of Ramsey and State of Minnesota, have invented a new and useful Grain-Elevator, of which the following is a specification.

10 My invention relates to grain elevators, and the main object is to provide a grain elevator so improved that the house or building of same will be a structure inexpensive to erect and yet of great strength and durability. Another object is to so arrange the rooms, bins and machinery in said building that convenience, speed and economy are attained thereby.

The main features by which I secure these 20 advantages consist of constructing the head house with a central open shaft in which the elevators and their connections are mounted, and arranging the bins in radial directions from said shaft to the outer walls of the house; and other arrangements which will hereinafter be fully described, reference being had to the accompanying drawings, in which:—

Figure 1 is a substantially diametrical 30 vertical section of my improved grain elevator. Fig. 2 is an enlarged central vertical section of the uppermost distributor, 53 in Fig. 1. Fig. 3 is a horizontal section on the line 3—3 of Fig. 1. Fig. 4 is a section on the line 4—4 of Fig. 1. Fig. 5 is Fig. 4 modified and with some parts omitted. Fig. 6 is a section on the line 6—6 of Fig. 1. Fig. 7 is a section on the line 7—7 of Fig. 1.

Referring to the drawings by reference 40 numerals, the main building or house of the elevator is preferably constructed of reinforced concrete and is formed of a hollow upright shell or body 8, a central hollow shaft 9 and intermediate floors 10, 11, 12, a hollow base 13, a main roof 14, a shaft roof 15 and a series of radiating walls 45, which are braced together by strong beams 46, as will presently be more fully described. Above the roofs the shells 8 and 9 are preferably given and form of battlements, 16 and 50 17 respectively.

The house may be of square, hexagon, octagon or any other form, but probably the cylindrical form which I have shown 55 is the best. The base 13 is formed with a funnel-shaped annular pit which is divided

into two dump pits, 18, 18^a, having inlets 19 controlled by shutters (not shown) and leading into the elevator shaft to elevators 20, 21 and 20^b which are located therein. The 60 base is also formed with a lateral extension 22 which constitutes a pit 23 for the usual scale 24, upon which grain cars 25 are weighed. In Fig. 4 is shown a car pulling device consisting of a suitably driven cable 65 drum 26 and a cable 27, the latter guided between two pulleys, 28 and 29, so as to pull a car in either direction on the track rails 30. 31 is a shed for cars on the track 30 and for other cars, 25^a, on the track 30^a. 70

From the car 25 the grain may be dumped through a grate 32 into the dump pit 18^a. The base is further formed with a series of bins 33, the tops of which are covered by grates 34 so as to allow grain or other stuff 75 to pass downward into them from portable feed mills, 35 and grain cleaners 36; said bins having controlled inlets 33^a into the elevator shaft.

At the opposite side of the house from the 80 car shed 31 is a wagon shed 37, for farmers to drive in their wagons, as 38, upon a dump scale 39, to be weighed and then their load of grain dumped down into an extension 40 of the dump pit 18. In the modified form 85 shown in Fig. 5 the wagon shed is dispensed with and the dump scale 39 is placed within the main head house, and the latter is provided with doors 41 and 42 for the wagons to pass through to and from the scale. In 90 Fig. 4 43 and 44 designate the beams of the adjacent scales 24 and 39 respectively.

The inner shell or shaft 9 and the outer shell 8 are firmly connected by a series of radial walls 45, which thus divide the annular space between the two shells into any desired number of spaces. Said radial walls or partitions are connected together by strong beams 46, which support the inclined floors 47 of any desired number of bins arranged above each other in annular sets or series about the elevator shaft. In the present illustration I have shown only three sets of bins, namely 48, 49 and 50 (see Figs. 1 and 3). In the bins 50 the floors are inclined 105 toward a central aperture 51, from which grain may be delivered through chutes 52 to the various machines 35, 36 on the work floor 12.

By the elevator 20—20^a—20^b grain is 110 hoisted and delivered into the upper distributor 53. The latter may be of any suit-

able form, but in Fig. 2 is shown how it may consist of a hopper 53 having a funnel-shaped bottom with several inclined distributing tubes 54, into either of which the 5 grain may be admitted through an aperture 55 in a false bottom 56, which is fixed on a vertical shaft or rod 57 having a handle 58 by which to turn it; said handle may be located on any of the floors 59, 60, 61, 62 10 of the elevator shaft. Said floors are reached either by a man-lift 63 or ladder steps 64 (shown in Fig. 3).

From some of the tubes 54 the grain passes directly through apertures 65 into the 15 bins 48, while from others of the tubes the grain passes through leader tubes 66 into the bins 49; and bins 50 are filled through leader tubes 67 from a distributor 68, which is like the one shown in Fig. 2, except that 20 it has only half as many outlet tubes. Said distributor 68 is supplied from the spout 69 and head 21^b of the elevator 21, 21^a, whose main function is to transfer grain from one car to another.

25 The two distributors 70 and 71 are alike in that they each comprise three compartments, as clearly shown in Fig. 3. The central compartment spout 72 of distributor 70 is arranged to spout into the central 30 compartment of distributor 71 below it, and of the latter compartment the spout 73 is provided with a flexible extension 74 which may be directed to either one of the machines on the work floor 12, as indicated 35 by the dotted lines 74 in Fig. 1, or may be directed into the pit 18, or 18^a, through the grates 34. The other two compartments of distributor 70 are provided one with a spout 75 for spouting grain into the car 25, and the other with a spout 76 for spouting into the car 25^a.

40 Of the two other spouts, 77 and 78, of distributor 71 the spout 77 is directed to the car 25 and spout 78 is left in readiness to receive a flexible tube (not shown), which may be directed to the bins 33, or pit 18, or any other place desired. From said pit 18 45 elevator 20^c (shown in Fig. 3) may elevate into distributor 53; said elevator is used alternately with the elevator 20^a, especially if the latter gets out of order. In Fig. 5 is shown how each floor in the elevator shaft is secured, like the floor 60 upon joists 60^x.

50 55 79 are spouts from the ports 80 for spouting the grain into either of the compartments of the distributor 70, and 81 are similar spouts leading from ports 82 into either compartment of the distributor 71. Short 60 spouts similar to 81 are employed at the ports 19 and 33^a in the base, but as such spouts are common they are not shown. All ports or passages for grain, wherever so required are provided with suitable shut-off 65 means (not shown) operable from within

the elevator shaft; and said shaft is provided with door openings 83 and the building with doors 83^a on the work floor and 84 on the top floor 10, 85, 86, 87 indicate windows, or doors, on the building. 70

The operation of the elevator having already been fairly stated it may simply be recapitulated as follows:

Receiving.—Wagons loaded with grain are run upon the dump scale 39 and after 75 being weighed the grain is dumped into the pit 18 and elevated by elevator 20—20^a, or elevator 20^c, into the distributor 53, from which the operator by turning the handle 58 and rod 57 allows the grain to run into the 80 bins 49. Car loads of grain are weighed on scale 24 and dumped into pit 18^a. From the latter pit the elevator 21—21^a carries the grain up into the head 21^b and distributor 68, from which latter the operator by 85 turning a handle and rod similar to that shown in Fig. 2, allows the grain to run into the bins 50.

All the bins 48 and about half of those 49 are used for cleaned grain, and all the 90 bins 50 and some of those 49 are used for uncleaned grain.

Cleaning and shipping.—When grain is to be cleaned it is either taken from bins 50 or from bins 49 through spouts 73—74 to 95 the cleaning machines on the main floor 12, and after it is cleaned it is passed into the bins 48, or some of those 49, from which bins all clean grain to be shipped is spouted to the cars. The screenings from the cleaning process are passed down through the grates 34 into some of the bins 33, while in the others of said bins may be stored ground feed from the feed mill. When said stuffs are to be shipped they are elevated into 100 some of the bins 49 and from there spouted into a car or wagon, as the case may be. The stuff may also be spouted from the outlet 51 in Fig. 1, after allowing it to pass into one of the bins 50; this is especially 110 practical with the modified form shown in Fig. 5, where the wagon path passes under one of the outlets 51.

Mixing.—To mix two or more grades of grain the several grades are simply spouted 115 together into one place.

Transferring.—To transfer grain from one car to another, the grain is simply dumped into the pit 18^a and elevated and allowed to run through a properly directed 120 spout into the car that is to receive it.

What I claim is:

1. In a grain elevator, a funnel-shaped base terminating in a central pit, a hollow upright cylindrical body constituting an 125 elevator shaft in said pit and having side inlets for grain into it near the bottom of the pit, and resting upon said base a larger hollow cylindrical body spaced concentrically about the elevator shaft, and a series 130

of radial partition walls connecting the said two bodies, whereby a series of compartments are formed between the said bodies and walls, and floors dividing said compartments into several sets of upper and lower bins, and suitable roofing covering said bodies and the spaces within the same.

2. The structure specified in claim 1, and 10 horizontal beams extending from one radial wall to the other to prevent bulging of said walls and support the floors of the bins.

3. The structure specified in claim 1, said 15 base having also several inlet openings for dumping grain into it, and elevators within the shaft for lifting the grain to any desired height, and means for distributing the lifted grain into any of the upper bins desired, and means for conducting grain from 20 any of said upper bins into cars to be load-

ed, and means for conducting grain from the upper bins to the lower bins above the main floor.

4. The structure specified in claim 1, grain 25 cleaning machinery on the ground floor, the latter floor having open grates for conveying stuffs from the cleaning machinery down through the floor, and portions of the base below said floor having bins below said grates; said bins having inlets 30 into the elevator shaft, and means for closing said inlets when so desired.

5. The structure specified in claim 4, feed 35 grinding machinery on the ground floor, bins for the feed below said floor and grates in the floors for the feed to pass through into the bins.

In testimony whereof I affix my signature.

JOHN H. A. BRAHTZ.
